United States Patent Office

Des. 232,093
Patented July 16, 1974

232,093

LAVATORY

Donald C. Schrock, 1013 N. West St.,
Nevada, Mo. 64772

Filed June 20, 1973, Ser. No. 371,793

Term of patent 14 years

Int. Cl. D23—02

U.S. Cl. D23—58

Fig. 1.

Fig. 2.

Fig. 3.

FIG. 1 is a top plan view of a lavatory showing my new design;

FIG. 2 is a front elevational view thereof;
 FIG. 3 is a right side elevational view thereof;
 FIG. 4 is a bottom plan view thereof;
 FIG. 5 is a rear elevational view thereof;
 FIG. 6 is a left side elevational view thereof; and
 FIG. 7 is a partial cross-sectional view taken along line 7—7 of FIG. 1.

I claim:

The ornamental design for the lavatory, substantially as shown.
